UNITED STATES PATENT OFFICE.

JUSTUS A. TRAUT, OF NEW BRITAIN, CONNECTICUT, ASSIGNOR TO THE STANLEY RULE AND LEVEL COMPANY, OF SAME PLACE.

DESIGN FOR A TOOL-HANDLE.

SPECIFICATION forming part of Design No. 26,768, dated March 16, 1897.

Application filed January 26, 1897. Serial No. 620,836. Term of patent 14 years.

To all whom it may concern:

Be it known that I, JUSTUS A. TRAUT, a citizen of the United States, residing in New Britain, in the county of Hartford and State of Connecticut, have invented and produced a new and original Design for a Tool-Handle, of which the following is a specification.

This invention relates to a design for tool-handles.

10 In the drawings accompanying and forming part of this specification, Figure 1 is a side elevation of a tool-handle, showing my design applied thereto. Fig. 2 is an edge elevation of the same; and Fig. 3 is a transverse section of the same, the section being taken in line *a a*, Fig. 1.

Similar characters designate like parts in all the figures of the drawings.

15 The leading feature of my design consists 20 in a tool-handle having a concavity in at least one side thereof, a reduced end, and a strip of ornamental material in at least one end of the handle.

The tool-handle has symmetrically-disposed concavities or grooves, an end reduced at both 25 sides of the tool-handle, and strips of ornamental material at both sides of both ends of the tool-handle.

2 and 2' designate, respectively, symmetrical grooves or concavities in opposite sides 30 of a tool-handle H.

4 designates a reduced end having both sides thereof reduced in thickness.

5 and 5' 6 and 6' designate strips of ornamental material at opposite sides of opposite ends of 35 the tool-handle H.

Having described my invention, I claim—
The design for a tool-handle, substantially as herein shown and described.

JUSTUS A. TRAUT.
